AUTO KICK PLATE

Ray F. Doyle, Alliance, Ohio, assignor to Everhard Products Inc., Canton, Ohio, a corporation of Ohio

Filed Aug. 28, 1964, Ser. No. 31,496

Term of patent 14 years

(Cl. D14—6)

FIG. 1 is a perspective view of an auto kick plate, showing my new design, the fragmentary portions of a vehicle shown in broken lines being included for illustrative purposes only;

FIG. 2 is a front elevation of the kick plate;
FIG. 3 is a top plan view of the kick plate;
FIG. 4 is a bottom plan view of the kick plate;
FIG. 5 is an end elevation of the kick plate; and
FIG. 6 is a vertical section taken on the line 6—6,
FIG. 2.

I claim:
The ornamental design for an auto kick plate, substantially as shown and described.
